(57) **CLAIM**

The ornamental design for a vehicle as shown and described.

DESCRIPTION

FIG. 1 is a top, front and right side perspective view of a vehicle showing our new design;

FIG. 2 is a top, rear and right side perspective view thereof;

FIG. 3 is a front elevation view thereof;

FIG. 4 is a rear elevation view thereof;

FIG. 5 is a right side elevation view thereof;

FIG. 6 is a top plan view thereof; and,

FIG. 7 is a bottom plan view thereof.

The broken lines in the figures are included for the purpose of illustrating portions of a vehicle and form no part of the claimed design.

1 Claim, 7 Drawing Sheets
